CATCH BASIN TRAP

James A. Parks, 2152 Leland Ave., Chicago, Ill.

Filed Mar. 9, 1964, Ser. No. 78,912

Term of patent 14 years

(Cl. D91—3)

FIG. 1 is a side elevational view of a catch basin trap, showing my new design;

FIG. 2 is a front elevational view;

FIG. 3 is a top plan view;

FIG. 4 is a rear elevational view; and

FIG. 5 is a bottom plan view

I claim:

The ornamental design for a catch basin trap, as shown.
